DOMESTIC APPLIANCE

Carel F. Abresch, Dayton, Ohio, assignor to General Motors Corporation, Dayton, Ohio, a corporation of Delaware

Application March 2, 1949, Serial No. 79,226

5 Claims. (Cl. 103—117)

1

This invention relates to domestic appliances, and more particularly to domestic washing machines or the like.

An object of this invention is to provide mechanism capable of imparting a vacuum and a super-atmospheric pressure alternatively in the casing of the washing machine or the like, which mechanism is automatically lubricated by liquid trapped in the mechanism.

Another object of this invention is to provide a pump structure for imparting a vacuum or super-atmospheric pressure alternatively in a washing machine or the like, which pump structure is adapted to arrest a portion of liquid, for use in lubricating the pumping mechanism within such a structure.

Further objects and advantages of the present invention will be apparent from the following description, reference being had to the accompanying drawings, wherein a preferred form of the present invention is clearly shown.

In the drawings:

Fig. 1 is a diagrammatic representation of the pump structure and a washing machine;

Fig. 2 is a partial view of the mechanism shown in Fig. 1, with the rotor of the pump reversed;

Fig. 3 is an enlarged view of the pump structure shown in Fig. 1;

Fig. 4 is a cross-sectional view taken along the line 4—4 of Fig. 3;

Fig. 5 is a top view of the mechanism shown in Fig. 3, with the cover removed;

Figs. 6 and 7 show modified forms of pump cylinder structures;

Fig. 8 shows the optional use of a check valve in the pump structure;

Fig. 9 is an enlarged cross-sectional view of a rotary seal suitable for use with the washing machine;

Fig. 10 is a cross-section along the line 10—10 of Fig. 9; and

Fig. 11 is an elevation, and Fig. 12 a cross-section, along the line 12—12 of a modified form.

According to this invention a casing, or washing machine, 10 is adapted to have vacuum and super-atmospheric pressure alternatively imparted thereto. By way of example, the washing machine 10 may be provided with a flexible diaphragm 11 secured to the casing 10. A pipe 12 is provided to supply water to the casing. A hinged cover 13 may be provided for inserting and removing clothes. The casing 10 is adapted to be rotated around the axis 14, 14 to impart a tumbling action to the liquid and clothes in the cas-

2

ing. A drain 15 is connected to the casing 10, and is adapted to rotate therewith. The pipes 12 and 15 are provided with rotating seals 16 to allow relative rotation. The drain 15 is connected to the pipe 17 leading to the pump structure 18. The drain 15 rotates past the low point in casing 10 at each revolution, and thus is adapted to empty the casing by repeated travel past this low point. A pipe 19 is provided for supplying hot and cold water from the valve structure 20 into the casing 10 through pipe 12. An outwardly directed, spring-pressed, check valve 21 is provided to allow excess air to escape when super-atmospheric pressure is produced in the casing 10. The portion 10a of the casing is perforated sufficiently to allow atmospheric air to enter and exert its pressure on the diaphragm 11, to collapse it against the clothes when a vacuum is produced in the casing.

The pump structure 18 may include first and second upper chambers 22 and 23 which are separated by a vertical wall 24. These chambers are connected at their lower ends, and at separate points 26 and 27, with a horizontally disposed, generally cylindrical, lower chamber 25. The connections between this chamber 25 and the chambers 22 and 23 are through openings 26 and 27 respectively which are formed on either side of the abutment wall 28 at the upper portion of the chamber 25. A pipe or conduit 29 is connected to the upper portion of the chamber 23 at one end, and is adapted to have its other end 30 hung over the rim of a stationary tub or the like 31 at a level higher than the normal working fluid level 32 within the washing machine.

A reversible pump piston or rotor 33 is mounted on the horizontal shaft 34 and preferably is provided with flexible fingers or blades 35. This rotor may have its outer body and fingers made of flexible material, such as of rubber, either natural or synthetic, or of any other rubber-like compounds now well known. Between the fingers 35, smaller knobs or beads 36 are provided, which tend to reduce the area between two successive fingers, when the fingers pass the abutment 28. This produces a pumping action, due to the decreased area between the fingers at this point.

Preferably the cross-sectional areas of the pipes 17 and 29 are smaller than the cross-sectional areas respectively of the chambers 22 and 23. The construction is such that, when a mixture of gas and liquid is being pumped by the rotor 33, a certain amount of liquid is trapped in one or the other of chambers 22 or 23, while the excess liquid is forced out the pipe 29. As shown in Fig. 3, the rotor 33 is rotating clockwise, and pumping gas (air) through the body

of liquid whose level is indicated at 40, the air being indicated by bubbles 41, which in actual use produce more turbulence than is diagrammatically indicated at 41. The gas continues through the pipe 29. A small amount of liquid passes with the fingers 35 past the abutment 28, and helps to maintain the pump structure cooled and lubricated. Should the rotor 33 of Fig. 3 be reversed, the liquid in chamber 23 will be transferred to chamber 22, and will reach a level 42 somewhat lower than level 40, since the chamber 22 is larger than chamber 23. This will permit the pump to pump air through the pipe 17 into the casing 10 without sending any liquid into the chamber 10 to wet the clothes therein. The condition shown in Fig. 2 occurs when water is maintained in casing 10 to wash the clothes, while the condition shown in Fig. 3 occurs when the clothes are dried.

In the embodiment shown in Figs. 3 and 4, the chamber 25 is substantially circular in cross-section, with the rotor shaft 34 at the center of the circle. The chamber 25 is provided with an offset abutment 28, which produces the pumping action. In the modification shown in Fig. 6, the chamber 25a is somewhat elliptical, and the rotor 33a rotates about an axis nearer the upper portion of the chamber 25a. In Fig. 7 the lower half of chamber 25b is semi-circular, with its radius about the point 50. The upper portion of the chamber 25b may be circular, with a much larger radius, with its center below the point 50. The shaft 34b has its center above the point 50 and produces a compressing action, as the fingers 35b pass around the upper portion of the chamber 25b.

In the modification shown in Fig. 8, a check valve 51 is placed between the chambers 22c and 23c. This check valve is spring-pressed a sufficient amount to impart the desired super-atmospheric pressure within the casing 10. If a check valve 51 is used, as shown in Fig. 8, then the check valve 21, shown in Fig. 1, may be omitted, if desired.

The rotary seals indicated at 16 in Fig. 1 may be of the construction shown in Figs. 9 and 10.

The pipes 15 and 17 of Fig. 1 for example, may be threaded on threads 60 and 61 respectively. The thread 60 is formed on a cylindrical fixture 62. This fixture has a smooth internal bore 63, and terminating in a flange 64. The fixture 62 has a smooth plane surface 65 adjacent the flange 64. A bearing ring 66, of self lubricating bearing metal composition, is placed over the fixture 62 and extends over the flange 64 at 67.

Another fixture 68 carries the thread 61 and is also provided with a smooth internal bore 69. This fixture terminates in a flange 70 which has a cylindrical extension 71. The extension 71 is externally threaded at 72. The flange 70 is provided with a smooth plane surface 73, in which an annular notch 74 is formed.

A rubber-like ring 75, of neoprene or the like, is placed in the notch 74, and thereafter the clamping ring 76 is threaded on threads 72. The ring 76 is provided with inward flange 77 which locks the bearing ring 66 in place. The ring 66, in turn, locks the fixture 62 in place by its action on flange 64. The action of ring 76 also compresses the rubber-like ring 75 slightly to make a water-tight construction at this point. A locking screw 78 holds the ring 76 in proper adjustment.

It is to be noted that the bearing ring 66 assumes all the bearing strains of the seal, while

the rubber-like ring 75 assumes all of the sealing functions. This produces a simple and efficient rotating seal, particularly adapted for use in a washing machine of the character herein disclosed.

In the operation of the machine, the cover 13 is opened preferably while it is at its upper position of travel, and clothes and detergent are inserted in casing 10. The cover 13 is then closed. Water of the desired temperature is admitted through the pipe line 19 by the operation of the valve structure 20, which mixes hot and cold waters from the usual supply pipes. Liquid is inserted approximately to the level 32. The casing 10 is then rotated in one direction, by belts (not shown) which are also connected to the pump rotor 33. At this time the rotor 33 rotates counterclockwise, as shown in Fig. 2, and pumps a certain amount of air into the casing 10 and maintains it at a slightly super-atmospheric pressure. The excess air flows out past check valve 21. This maintains the diaphragm 11 in the position shown in Fig. 1, distended against the wall 10a. The water and clothes are tumbled by suitable baffles 36 in the casing 10. After a suitable time, the rotation of the casing 10 and rotor 33 are reversed, causing the water to be pumped out of the casing 10 and to be discharged into the stationary tub 31, as shown in Fig. 1. The pumping of liquid continues until the casing 10 is emptied, it being noted that the pipe 16 rotates repeatedly past the lowest portion of the casing 10 to completely empty the water. Thereafter continued rotation pumps out the air remaining in the casing 10, the air bubbling through the liquid trapped in the chamber 23, as shown in Fig. 3, and is discharged through the pipe 29. This action imparts a vacuum within the chamber 10, and causes the diaphragm 11 to be pressed against the clothes to squeeze them dry. After the drying or squeezing action has proceeded a sufficient length of time, rotation is again reversed, to pump a certain amount of air into the casing 10, to break the vacuum therein, and to force the diaphragm 11 to its distended position. At the time of this reversal, the liquid in casing 10 is transferred from chamber 23 to the dotted position 42 in chamber 22, which permits pumping air without water into casing 10.

Thereafter one or more rinsing actions can be performed by introducing water without detergent and agitating and squeezing the clothes in the same manner as for washing.

Figs. 11 and 12 show a modification of a pump, which may be connected to the system shown in Fig. 1 at 17 and 25. The inlet 80 may be connected to the pipe 17, and the outlet 81 may be connected to the discharge pipe 29. The casing 82 is provided with a cover 83 which is bolted thereto. A shaft 84 carries a hub 85 on which is mounted a rubber-like rotor 86 having radial fingers 87. The rotor 86 is placed inside of a partly cylindrical inner casing 88, which has an eccentric portion 89. A copper lining 90 is provided inside of the casing 88. An outlet opening 91 is placed between the inner portion of the casing 88 and the inner portion of the casing 82. The casing 88 is substantially surrounded with liquid which is trapped in the casing 82, when liquid with or without air is being pumped from the inlet 80 to the outlet 81. A baffle 92 is built in the casing 82 for the purpose of trapping liquid, when the mixture of liquid and air are being pumped.

In the operation of this modification, when liquid alone, or liquid in air, are being pumped from 80 to 81, by rotation of the rotor in a clockwise direction, liquid is trapped in casing 82, and surrounds the inner casing 88. Any heat which is generated in the rotor 86, is dissipated to the liquid in the casing 82, thus preventing any high temperature within the rotor.

While the form of embodiment of the invention as herein disclosed, constitutes a preferred form, it is to be understood that other forms might be adopted, as may come within the scope of the claims which follow.

What is claimed is as follows:

1. A pump including a rotary impeller, said impeller being provided with a plurality of substantially uniformly spaced blades, a casing surrounding the impeller fitting against the ends of the blades and extending into contact with the tips of the blades and forming an impeller chamber, said casing having an inlet and an outlet communicating with the impeller chamber, said impeller being provided with axially parallel rounded radially projecting beads between every two adjacent blades extending a lesser distance from the axis of rotation than the blades, a portion of the casing between the inlet and the outlet being sufficiently near the axis of the impeller to fold the blades into substantially continuous engagement with the adjacent portion of said beads from the inlet to the outlet so that the beads act like a bending fixture to force uniform bending of the blades as the impeller rotates, said blades being formed principally of a flexible rubber-like material.

2. A pump including a rotary impeller, said impeller being provided with a plurality of substantially uniformly spaced blades, a casing surrounding the impeller fitting against the ends of the blades and extending into contact with the tips of the blades and forming an impeller chamber, said casing having an inlet and an outlet communicating with the impeller chamber, said impeller being provided with axially parallel rounded radially projecting beads between every two adjacent blades extending a lesser distance from the axis of rotation than the blades, a portion of the casing between the inlet and the outlet being sufficiently near the axis of the impeller to fold the blades into substantially continuous engagement with the adjacent portion of said beads from the inlet to the outlet so that the beads act like a bending fixture to force uniform bending of the blades as the impeller rotates, said blades and said beads being formed principally of a flexible rubber-like material.

3. A pump including a rotary impeller, said impeller being provided with a plurality of substantially uniformly spaced radially extending blades, a casing surrounding the impeller fitting against the ends of the blades and extending into contact with the tips of the blades and forming an impeller chamber, said casing having an inlet and an outlet communicating with the impeller chamber, said impeller being provided with axially parallel half round radially projecting beads extending substantially the entire distance between every two adjacent blades in the axial direction and extending a lesser distance from the axis of rotation than the blades, a portion of the casing between the inlet and the outlet being sufficiently near the axis of the impeller to fold the blades into substantially continuous engagement with the adjacent portion of said beads from the inlet to the outlet so that

the beads act like a bending fixture to force uniform bending of the blades as the impeller rotates, said blades being formed principally of a flexible rubber-like material.

5. A pump including a rotary impeller, said impeller being provided with a plurality of substantially uniformly spaced radially extending blades, a casing surrounding the impeller fitting against the ends of the blades and extending into contact with the tips of the blades and forming an impeller chamber, said casing having an inlet and an outlet communicating with the impeller chamber, said impeller being provided with axially parallel half round radially projecting beads extending substantially the entire distance between every two adjacent blades in the axial direction and extending a lesser distance from the axis of rotation than the blades, a portion of the casing between the inlet and the outlet being sufficiently near the axis of the impeller to fold the blades into substantially continuous engagement with the adjacent portion of said beads from the inlet to the outlet so that the beads act like a bending fixture to force uniform bending of the blades as the impeller rotates, said blades and said beads being formed principally of a flexible rubber-like material.

5. A reversible pump for both liquids and gases including a casing, a reversible rotary impeller having means in sealing contact with the inner walls of the casing, said casing having at least two openings above the impeller interchangeable for intake and discharge upon reversal of the impeller, a first reservoir extending above and communicating with one of said openings, a second reservoir extending above and communicating with the second of said openings, said first reservoir having a capacity exceeding the net fluid space within the casing, said second reservoir having a capacity substantially exceeding the capacity of the first reservoir, said reservoirs each having an opening adjacent their top interchangeable for intake and discharge upon reversal of the impeller.
